TELEPHONE STATION

Edmund H. Yaeger, Longmont, Colo.

Application June 15, 1936, Serial No. 85,310

3 Claims. (Cl. 248—123)

This invention relates to improvements in telephone pay stations.

It frequently occurs that tourists and other drivers of automobiles find it necessary to use the telephone, and in order to do so, they must first park their cars, and go into a building where public phones are to be found. Strangers do not, as a rule, know where the public telephones are located, and after they have been located, they must discover a parking place, which is often very difficult.

It is the principal object of this invention to provide an outside telephone stand, preferably of the pay-station type, that can be located at points along the streets, along highways, in parks and in filling stations and which can be used by occupants of automobiles without leaving the same.

An important object of the invention is to provide in adjacency to a telephone stand of the above stated character, a barrier or fender in the form of a fence railing post or curb which establishes the position of a motor-vehicle relative to the stand, so that an occupant of the same may reach the telephone for use, without leaving the vehicle.

The barrier at the same time protects the telephone instrument and stand from being damaged by a vehicle coming accidentally in contact therewith.

It is another object of the invention to provide in association with a telephone instrument mounted on a stand as hereinabove described, means for moving the instrument from the stand to within easy reach of the occupant of the vehicle, means to automatically return the instrument to its original position, means for enclosing the instrument when not in use so as to protect it from the weather, and several other details of construction, all of which will fully appear in the course of the following description.

The above and other objects that may become apparent as the description proceeds are attained by means of a construction and relationship of parts that will now be described in detail, reference for this purpose being had to the accompanying drawings in which the invention has been illustrated and in which:

Figure 1 is a vertical section of a telephone stand, showing an automobile positioned adjacent the same and showing, by dotted lines, the position of the telephone when in use;

Figure 2 is a front elevation of the upper portion of the station, the telephone being retracted and the doors of the housing closed;

Figure 3 is a plan showing a plurality of duplex stations arranged on an elongated isle of safety and surrounded by a U-shaped driveway;

Figure 4 is a plan view showing a single telephone stand on an isle having a curb constituting the barrier which, as stated above, determines the position of a motor vehicle relative to the stand; and

Figure 5 is a front elevation of the telephone, showing it provided with a unitary transmitter and receiver.

In the drawings numeral 6 designates the upper surface of the roadway, street or park on which the automobile 7 is supported. Numeral 8 designates the upper surface of a concrete platform, isle of safety or sidewalk, and 9 the post which supports the housing 10, in which the telephone is stored when not in use.

The post 9 is preferably made of concrete, although any other suitable material can be employed, such as brick, stone or iron.

A large pipe 11 extends from the bottom to a point near the top of the post and when the latter is made from moldable material, the pipe 11 is put into the mould before the material and becomes a non-removable part of the post. A conduit 12 extends entirely through the post and contains light wires for the sign 13.

A conduit 14 extends upwardly from the bottom of the post to a point 15, where it makes a right angle turn and terminates in a bell box 16. Conduit 14 is provided with a T 17 from which a short length of conduit projects which terminates in an outlet box 18. An arm 19 is provided at its inner end with an opening thru which the conduit 14 extends, and the outer end of this arm has a vertical pivot 20. The upper end of pivot 20 is provided with an opening for the reception of the bail of the padlock 21.

A box or housing 10 of substantially cubical shape, has a bottom 22 that rests on the brackets 23 and an end wall 24 that fits against the outer surface of the post. Wall 24 has openings for the conduit 14, another for the branch from the T, and also an opening for arm 19, and is secured to the post by suitable means. The front end of the housing is formed by two doors 25 secured to it by means of spring hinges 26 that tend to keep them in closed position. The adjacent edges of the doors have cut-outs 27 that form an opening for the handle 28 which projects forwardly from the upper end of the telephone 29.

A lazy tong support 30 has its inner end attached to the sleeve 31 through which the pivot 20

20 extends, and is locked in position thereon by means of the padlock. The telephone is provided with two rearwardly projecting brackets 32 to which the other end of the lazy tong is attached. Since the lazy tong support is common, it has been shown more or less diagrammatically. A pulley 33 is provided near the top of the pipe 11 and a cord 34 passes around this pulley and into the housing 10 where it terminates in a snap 35. The other end of the cord has a weight 36.

The post is provided near its lower end with an opening 37 that is closed by a door 38. The door and opening provide access to the pipe 11, for the purpose of attaching the weight or replacing the cord in case it breaks. The telephone is provided on its rear side with a ring 39 for engagement with the snap.

The weight 36 and cord 34 serve to retract the telephone after it has been used. A box 40 is attached to the bottom of the telephone and serves as a receptacle for the telephone directory 41.

A plate 42, having rounded corners 43, is carried by the telephone and serves to open the doors 25 and to hold them open when the telephone is in use.

An elastic cord 44 has one end attached to the telephone and the other provided with a hook 45. The telephone is provided with the usual transmitter 46, receiver 47 and dial 48.

When the "French type" shown in Figure 5 is used, both the receiver and the transmitter are carried by the member 49.

Referring now more particularly to Figure 1, it will be seen that the wheel 50 of the automobile is placed adjacent to the guide wall or curb 51. The driver is now in position to reach the handle 28, and by exerting a pull thereon, the telephone is moved into the position designated by dotted lines. The hook 45 can be anchored to the door handle 52, or to some other stationary portion of the car for the purpose of holding the telephone while it is being used. After the call has been made, the hook 45 is released and the weight 36 pulls the telephone back into full line position.

In Figure 4, a circular base 8a has been shown with a segment removed. The wall 51 forms a guide for the car.

In Figure 3 a base or isle of safety 8b has been provided which is of sufficient length to accommodate three cars, and the stations are double, so that two people can use the same station.

The arrows indicate the path of the cars into and out of the space reserved for the telephones. The stations are each provided with a bell 16 so that long distance calls can be perfected from them.

The telephones are arranged so that they can be easily removed and replaced if it should be found desirable to remove them at night. The cord 52 is provided with a plug 53 so that connection can be quickly made at the outlet 18. By removing the lock 21, the telephone can be disconnected from the pivot 20.

It will be apparent from the above that outside telephone pay stations of the type described are a great convenience, as it makes it possible to telephone without first finding a parking place, and even without leaving the automobile. Telephone stations of the kind described can be constructed at a reasonable cost, and can

be located at convenient places in down town sections, parks, along the highways, etc.

Attention is called in particular to the guide wall 51 that serves to space the automobile the proper distance from the station, as this makes it possible to get the automobile properly positioned without any special effort. In this connection, it should be clearly understood that the guide wall as shown and described, is merely a convenient and practical means for providing a barrier or fender which determines the position of a motor vehicle relative to the telephone stand so that the instrument may be moved within easy reach of the occupant of the vehicle. Other barrier means such as a fence or a post, or a railing or the like may be employed within the spirit of this invention.

It should further be understood that while for the purposes of this invention, it is desirable to employ telephone instruments of the pay-station type, it is well within the range of possibilities, especially where a number of the stands are placed within a limited area, as is illustrated in Figure 3, to use ordinary instruments, in which case the money required for the use of the telephones, is collected by an attendant.

In addition to determining the position of motor vehicles with respect to the telephone stands, the barriers are also useful and in fact essential to prevent careless drivers from damaging the stands and the instruments mounted thereon, from being damaged by impact of the vehicles.

The elastic cord 44 makes it possible to anchor the telephone to various types of automobiles, as it will stretch sufficiently to reach the door handle, or steering wheel of any type of car. The cord 44 is weak, compared to the other parts, so that it will break without doing any damage, if the car should be moved before the hook has been disconnected.

Having described the invention, what is claimed as new is:—

1. An outside telephone station, comprising in combination, a hollow supporting post, a weight in the post, a pulley near the upper end thereof, a flexible tension member having one end connected to the weight and the other passing over the pulley and to the outside of the post, a housing secured to the post, the flexible member terminating in the housing, a pivot pin in the housing adjacent the inner end thereof, the outer end of the housing being open, a lazy tong support removably attached to the pivot, a telephone attached to the outer end of the support, means for effecting a quick detachable connection between the flexible member and the telephone, whereby it will be retracted into the housing when not in use, and an elastic member secured to the telephone and provided at its free end with means for making connection with a stationary member to hold the telephone extended in opposition to the action of the weight.

2. Means for supporting a telephone comprising a hollow supporting post, a weight in the post, a pulley near the upper end thereof, a flexible tension member having one end connected to the weight and passing over the pulley to the outside of the post, a housing on the post, the flexible member having its free end normally within the housing, an extensible carrier for the telephone normally within the housing, and means connecting the free end of the flexible member to the carrier whereby the latter will be retracted by the action of the weight after extension.

3. Means for supporting a telephone comprising a hollow supporting post, a weight in the post, a pulley near the upper end thereof, a flexible tension member having one end connected with the weight and passing over the pulley to the outside of the post, a housing on the post, the flexible member having its free end normally in the housing, an extensible carrier for the tele-

phone normally inside the housing, means for effecting a detachable connection between the flexible member and the carrier whereby the latter will be retracted into the housing after extension, by the action of the weight, and means for holding the carrier in an extended position by connection with a relatively stationary object.

EDMUND H. YAEGER.
